UNITED STATES PATENT OFFICE.

EDWARD DAVOCK, OF NEW YORK, N. Y.

HEATING SYSTEM.

1,407,990.

Specification of Letters Patent. Patented Feb. 28, 1922.

Application filed November 14, 1917, Serial No. 202,004. Renewed March 30, 1921. Serial No. 457,052.

To all whom it may concern:

Be it known that I, EDWARD DAVOCK, a citizen of the United States, residing at New York, in the county and State of New York, have invented certain new and useful Improvements in Heating Systems, of which the following is a full, clear, and exact specification.

My invention relates to heating systems and especially to steam boilers.

The preferred object of the invention is to provide an economical device for heating liquids or vapors.

Another object of the invention is to provide, in connection with a steam boiler, means for heating water for domestic use, for room heating, or for other purposes. It is the aim of the invention to utilize the waste heat in the combustion chamber of a boiler for heating water for use as feed water or for other uses, thus doing away with the expense of installing and maintaining the separate heaters generally employed for these purposes.

25 The water heater is adapted to be installed in the combustion chamber of a steam boiler when the latter is built, or it may be placed in an old or already built combustion chamber at any time during repairs.

30 The invention will be first hereinafter described in connection with the accompanying drawings, which constitute part of this specification, and then more specifically defined in the claims at the end of the description.

In the accompanying drawings, where in similar reference characters are used to designate corresponding parts throughout 40 the several views:—

Figure 1 is a longitudinal vertical section through the setting of an ordinary form of steam boiler, showing a water heater mounted in the rear wall thereof and connected up with a domestic hot water tank, and Figure 2 is an inner face view of the water heater, showing the arrangement of pipes extending into the combustion chamber of the boiler.

45 The boiler proper 1 is mounted in the usual setting, including the top cover 2 and rear wall 3, and under the boiler the usual fire wall 5, separates the combustion chamber 4 from the fire box 6, while the grate 7 at the bottom of the fire box separates the same from the ash pit 8. The products

of combustion from the fire box pass over the wall 5 into the combustion chamber, thence up along the back wall between it and the rear end of the boiler, thence below 60 the back arch 100 and through the flues or tubes of the boiler, and finally up to and through the chimney 9.

The water heater 14 is preferably placed in the rear wall of the combustion chamber, 65 and has a plurality of circulating pipes projecting therefrom, into the combustion chamber 4, as shown at 15. Water may be supplied to the heater 14 by a pipe 16 from any suitable source, and the hot water 70 may be distributed through the pipe 18. It will be understood that pipe 18 may be connected up with various heating appliances and the hot water may be conducted for use anywhere, and for any desired purpose: 75 The circulating pipes 15 add greatly to the heating surface of the heater 14, because of their being surrounded by the products of combustion whirling in the combustion chamber and, therefore, greatly add to the 80 efficiency of the heater, and when used as a feed water heater, will greatly increase the efficiency of the boiler. By reason of the position of the water heater, none of the gases that flow direct from the fire box, 85 through the flues to the stack and which are required to heat the water in the boiler, are used for heating said water heater, direct, but rather the slow moving whirling gases that follow the boiler setting and which also 90 give up some of their heat to the brick-work, supply the necessary heating. These, and only these, are the heat units utilized in the present improvement and, consequently, little or no more fuel is required for the 95 uses intended, when the hot water heater is placed in the walls of a combustion chamber, than would have been required for operating the boiler without the hot water heater attached thereto.

100 The hot water heater may be connected up with a domestic hot water tank 17, the water running from the tank to the heater through pipe 16, and from the heater to the tank through pipe 18. The heated water 105 may be distributed via pipe 19 and used for domestic or other purposes.

110 It will be noted that in obtaining the benefits I obtain from my heater I do so without in any way interfering with the circulation of the heat units which are generated in the fire box 6 and pass through the combustion

chambers 4, and that by placing my heater in the back wall of the combustion chamber, I obtain the desired results. In this invention, I utilize or depend upon the whirling heat units, heretofore valueless and somewhat detrimental, for heating my heater and the water it may contain for the purposes above set forth, and while I have shown my heater by way of example as located or set 10 in the back wall of a combustion chamber, I do not wish to be restricted to this one position, for it may be desirable to place same elsewhere, for instance, in the fire wall or sides of a combustion chamber so that the 15 whole interior of said chamber may be lined with them.

Having thus described my invention, what I claim as new and desire to secure by Letters Patent of the United States is:—
20 1. The combination with a steam boiler and the setting for the combustion chamber thereof, of a water heater imbedded in the wall of the setting, a plurality of circulating pipes projecting from the water heater 25 into the combustion chamber, and means for

circulating water through said heater, the circulation of the imbedded water heater being independent of the boiler operation.

2. The combination with a steam boiler and the setting for the combustion chamber thereof, of a water heater imbedded in the wall of the setting, a plurality of circulating pipes projecting from the water heater into the combustion chamber, and means for circulating water through said heater, the circulation of the imbedded water heater being independent of the boiler operation. 30 35

3. The combination with a steam boiler and the setting for the combustion chamber thereof, of a water heater imbedded in the rear wall of the setting below the back arch, a plurality of circulating pipes projecting from the water heater into the combustion chamber, and means for circulating water through said heater, the circulation of the imbedded water heater boiler being independent of the boiler operation. 40 45

In testimony whereof I have signed my name to this specification.

EDWARD DAVOCK.
